Primary Examiner — Manpreet Matharu*Assistant Examiner* — Keith Wilson(74) *Attorney, Agent, or Firm* — Au, LLC; Adam E. Urbanczyk(57) **CLAIM**

The ornamental design for a wine rack, as shown and described.

DESCRIPTION

FIG. 1. is a front left perspective view of a wine rack;

FIG. 2. is a rear left perspective view thereof;

FIG. 3. is a left side view thereof;

FIG. 4. is a front view thereof;

FIG. 5. is a right side view thereof;

FIG. 6. is a rear view thereof;

FIG. 7. is a top view thereof; and,

FIG. 8. is a bottom view thereof.

The broken lines, within the claimed design, on FIG. 3 are for illustrative purposes only and do not form a part of the claimed design.

1 Claim, 4 Drawing Sheets(56)
